(57) **CLAIM**

The ornamental design for a pan handle, as shown and described.

DESCRIPTION

FIG. 1 is a rear perspective view of a handle showing my new design;

FIG. 2 is a front perspective view thereof;

FIG. 3 is a rear view thereof;

FIG. 4 is a front view thereof;

FIG. 5 is a right side view thereof;

FIG. 6 is a left side view thereof;

FIG. 7 is a top view thereof; and,

FIG. 8 is a bottom view thereof.

The different shading techniques used in the figures depict a contrast of appearance only and do not represent a particular color, material or texture. The designations of rear, front, right, left, top and bottom are for reference purposes only. Shadows and reflections on various elements do not form any part of the claimed design and the design includes these elements without such reflections and shadows.
